E. H. Eden INVENTOR

BY Victor J. Adams

ATTORNEY

UNITED STATES PATENT OFFICE.

EDWARD H. EDEN, OF ST. LOUIS, MISSOURI.

SNOW SHOVEL.

Application filed May 20, 1927. Serial No. 193,020.

My present invention has reference to a snow shovel and my object is the provision of an implement for this purpose of such construction and arrangement that when the same is moved longitudinally over a bed of snow it will cut a furrow or path through the snow and cause the snow to be delivered at one side of the implement, while each successive longitudinal movement of the implement widens the path so that the last operation will throw all of the snow off of the walk onto a lawn, street or the like.

Specifically the improvement comprises a flat segmental blade having its rounded edge flanged upwardly, and being provided with a pivotally supported handle that is swingable to align with either of the straight edges of the blade and secured thereon, whereby the handle may be arranged to propel the implement at different angles through a bed of snow.

The drawings illustrate a satisfactory embodiment of the improvement.

In the drawings:

Figure 1 is a side elevation of a snow shovel in accordance with this invention.

Figure 2 is a top plan view.

Figure 3 is an edge view.

Figure 4 is a front elevation of the blade.

As disclosed by the drawings I make use of a flat segmental blade 1. The rounded end of this blade provides the back of the instrument and this edge is flanged upwardly, as at 2. Pivoted in a line with the center of the back and at the apex of the blade there is a handle 3. The handle is arranged, of course, on the under face of the blade, and the blade, at points equidistant from the center thereof, and adjacent to its flanged back is provided with openings 4 through either of which there is passed a headed pivot 5. The pivot also passes through an opening in the handle 3.

Preferably the pivot is in the nature of a bolt member and is engaged by a wing nut 6. 45

By securing the handle in either of the openings 4 the said handle will be arranged in a line with one of the straight angle edges of the blade. Thus the opposite angle edge becomes the active edge of the blade. By 50 moving the shovel longitudinally the snow will be gathered onto the blade and will be brought to contact with the flange 2 and moved therefrom off of the blade. By this arrangement it will be seen that a path or 55 furrow will be cut by the blade through a body of snow and by each successive operation of the blade along the side of such path will widen the said path or furrow and that the final operation of the implement, along 60 these lines, will direct all of the snow off the path and onto a lawn, street or other surface along the side of the path.

With my improvement snow can be removed and automatically directed away 65 from a path made thereby in an easy and expeditious manner. The improvement entirely obviates the necessity of lifting the shovel and throwing the snow to one side as is customary with such class of implements. 70

Having described the invention, I claim:

A snow shovel comprising a flat segmental blade whose rounded edge is flanged upwardly, a handle on the upper face of the 75 blade pivoted thereto centrally with respect to the flange and to the apex of the blade, said blade at points equidistant from the pivot, and adjacent to the flange having openings therethrough, and a holding means 80 designed to be passed through said openings and through the handle for holding the handle in a line with either of the angle edges of the blade.

In testimony whereof I affix my signature.

EDWARD H. EDEN.
